FOREIGN PATENT DOCUMENTS

JP 674007 S 3/1986

* cited by examiner

Primary Examiner — Karen S Acker

(74) Attorney, Agent, or Firm — Oblon, McClelland, Maier & Neustadt, L.L.P.(57) CLAIM

The ornamental design for a non-woven textile, as shown and described.

DESCRIPTION

The sole FIGURE is a plan view of a non-woven textile showing my new design.

The broken line perimeter surrounding the design indicates the boundaries of the claim and forms no part thereof.

1 Claim, 1 Drawing Sheet
